BOBBIN STRIPPER

Richard J. Haug, Nashua, N. H.

Application October 28, 1949, Serial No. 124,108

12 Claims. (Cl. 28—20)

1

My invention relates to machines for removing unused yarn from bobbins and in particular to means for the stripping from bobbins such yarn as is difficult to remove therefrom and is not removable by present machinery.

The principal object of the invention is to oscillate the bobbin having the unused yarn upon it and at the same time to cause the bobbin to move away from members which engage the yarn thereon.

The principal feature of the invention consists in exerting a downward pull upon the unused yarn on the bobbin while it is being oscillated.

Other and more specific features of the invention, residing in advantageous forms, combinations and relations of parts, will hereinafter appear and be pointed out in the claims.

In the drawings.

Figure 1 is a front elevational view of the machine, a portion of the housing thereof being broken away for clarity.

Figure 2 is a side elevational view of the machine.

Figure 3 is a view partly in section and partly in elevation of the lower portion of the machine.

Figure 4 is an enlarged top plan view of the machine.

Figure 5 is an enlarged sectional view taken on line 5—5 of Figure 1.

Figure 6 is an enlarged sectional view showing the means for operating the ripping rollers.

Figure 7 is a plan view of the cleaning jaws which may be used in place of the ripping rollers to remove unused yarn from the bobbin.

Figures 8, 9 and 10 are sectional views taken on lines 8—8, 9—9 and 10—10, respectively, of Figure 3.

In the drawings, 1 represents the base of the machine from which three members 2, 3 and 4, respectively, extend upwardly and which at their upper ends may be connected by cross pieces or the like 5. Extending upwardly between two of the upright members is a shaft 6 for operating other movable parts of the machine to be described. At its lower end, it is provided with a pulley or the like 7 for receiving a belt or similar means through which power is delivered to shaft 6. Just above the pulley 7 is a bevel gear 8 which meshes with a bevel gear 9 for operating a stub shaft 10.

On the operating shaft 6 and above the bevel gear 8 is a worm 11 for operating a worm gear 12 for purposes hereinafter to be described. At its upper end, shaft 6 is formed with an eccentric or cam 13 which rotates within a collar or the

like 14. The collar 14 which surrounds the eccentric is formed with a rigid link or the like 15 which may be pinned, as at 16, to extensions of a bushing 17 splined adjacent the upper end of a shaft 18. By means of the eccentric 13 rotating within the collar 14 which is connected to the splined shaft 18, it will be perceived that the splined shaft is continually oscillated.

The worm gear 12 is mounted upon a transverse shaft 19 on which is rigidly mounted a heart-shaped cam 20. In engagement with the periphery of cam 20 is a roller 21 mounted on the lower end of an upright member 22 which at its upper end is connected to the splined shaft 18 by an arm 23. The member 21 is vertically slidable within a suitable groove which may be conveniently formed in one of the upright members. A cover 24 may advantageously be formed over the member 21 so as to maintain it in its groove.

The lower end of the splined shaft 18 is provided with a clutch mechanism having a pair of jaws 25 for gripping the head of a bobbin 26 which contains the remains of unused yarn adjacent its head. The inner faces of the jaws are preferably formed with a friction lining to engage the wood of the bobbin and yet not press on the rings surrounding the head of the top of the bobbin because pressing on the rings would in time loosen them.

Jaws 25 are pivotally mounted at the lower end of the splined shaft 18, as indicated at 27. At their upper ends, the jaws are bifurcated as at 28 and they are provided with rollers 29 for engagement with a transverse member 30 of a vertically slidable device 31. By arranging the transverse member 30 so as to engage the rollers 29, the jaws are forced apart into engagement with the head of an associated bobbin.

Transverse member 30 formed at the lower end of the vertically slidable device 31 has an upwardly spaced portion 32 which, when the splined shaft is elevated, moves downwardly into engagement with the rollers 29 of the jaws and forces them outwardly as shown in dotted line in Figure 3. Extending upwardly from and preferably formed integrally with plate 32 is a rod 33 whose upper end extends into a bored out portion 34. Connected to the rod 33 by one or more pins 35 is a member 36 which, when the splined shaft is elevated, is adapted to be engaged by the upper outer end 37 of a bell crank lever 38 pivoted at 39 to the machine.

The upper end of the bell crank lever is formed with an elongated slot 40 for receiving a pin

41 carried by a lever 42 which is actuated in timed relation with vertical movement of the splined shaft 18 to engage the member 36. The lower end of lever 42 is provided with a roller 43 for engagement with an arm 44 which is rigid with shaft 19. Any suitable means, such as a spring 45 which is anchored to upright member 4 of the machine may be conveniently employed to cause lever 42 to rotate in a clockwise direction as viewed in Figure 3 of the drawings and thereby normally move bell crank 38 into the position shown.

It will be appreciated that the bell crank 38 moves into the position shown in Figure 3 when the roller 21 moves into the depression in cam 20 and that, when approximately in this position, arm 44 moves from contact with roller 43, thus permitting spring 45 to again cause lever 42 to move in a counter-clockwise direction and bell crank 38 to move in the opposite direction, so that the lower outer end 46 of the bell crank is elevated to engage the member 36 of the vertically sliding device and thus cause the transverse member 30 to move from between the rollers 29 of the jaws 25, thereby causing the jaws to release the head of the bobbin which has been worked on and to be in position to engage the head of the next bobbin fed to the machine.

As the bobbin is moved upwardly all unused yarn remaining on it is quickly stripped therefrom by serrated or ripping rollers 47 which have concaved peripheries so that their diameter is somewhat larger than the body of the bobbin and will, therefore, not touch or scar it. The rollers 47 are preferably removably screwed in place, as shown in Figure 6 of the drawings, and receive their motion from stub shaft 10 having at its inner end a bevel gear 48 meshing with another bevel gear 49 which by being rigidly connected to a shaft 50 causes it to rotate. Rigid with shaft 50 is a gear 51 which meshes with a similar gear 52 to drive shaft 53 into which the associated serrated or ripping roller is screw threaded.

Instead of employing the serrated or ripping rollers 47, they may be quickly unscrewed from the shafts in which they are mounted and the cleaning of the bobbin may be accomplished by using a pair of relatively soft jaws 54. The jaws 54 are in the main of metal 55 beyond which relatively soft material 56 projects. One of the jaws 54 is provided with an arm 57 which overlaps and extends beyond the other jaw 54. Arm 57 and the other jaw are each provided with racks 58 between which a pinion 59 is mounted for operating them in timed relation with the movement of the splined shaft 18. As shown most clearly in Figures 1 and 3, the soft jaws are operated by a link 60. The link is bent intermediate its ends and at that point it is provided with a roller 61 for engagement with a cam 62 which is also mounted on the transverse shaft 19. At its upper end, link 60 is pivotally connected as at 63 to a bracket 64 and at its lower end it is pivotally connected to the outer end of arm 57. It will thus be seen that, as roller 61 of link 60 tracks with the cam 62, movement of the jaws 54 into engagement with unused yarn on the bobbin will be accomplished because, as shown in Figure 7, as arm 57 moves to the right, it rotates pinion 59 which, being in engagement with the rack on the other jaw, causes it to move in a direction opposite to the direction of movement of the other jaw to which link 60 is pivotally connected.

Whether the serrated or ripping rollers 47 or the soft jaws 54 are employed, it will be appreciated that, when these different members are in engagement with the unused yarn on the bobbin, the bobbin is oscillated as well as being moved upwardly and downwardly.

Although I have illustrated and described the preferred embodiment of my invention, it will be apparent that modifications may be made in the device without departing from the spirit and scope of the appended claims.

What I claim is:

1. A bobbin stripping machine having a vertically extending shaft provided with jaws for holding the head of a bobbin with unused yarn remaining thereon, means for oscillating said shaft with the bobbin held in said jaws, means for causing said shaft to reciprocate vertically while oscillating, and means for engaging yarn on said bobbin to strip the yarn therefrom.

2. A bobbin stripping machine having a vertically extending shaft provided with jaws for holding the head of a bobbin with unused yarn remaining thereon, means for causing said shaft to oscillate while the bobbin is held in said jaws, means for moving said shaft vertically, and means for engaging the yarn on the bobbin to strip the yarn therefrom.

3. A bobbin stripping machine having a vertically extending shaft provided with jaws for holding the head of a bobbin with unused yarn remaining thereon, means for engaging the yarn on the held bobbin, a second vertically extending shaft having means for oscillating the shaft provided with jaws, and said second shaft rotating a cam for causing the shaft with the jaws to move upwardly while oscillating.

4. A bobbin stripping machine having a pair of upwardly extending shafts, one of said shafts being provided with jaws for holding the head of a bobbin with unused yarn remaining thereon, the other of said shafts being provided with means for oscillating the shaft provided with jaws and being also provided with means for reciprocating said last mentioned shaft, and means operable by said second named shaft for engaging the yarn remaining on said bobbin.

5. A bobbin stripping machine having a plurality of upwardly extending substantially parallel shafts, one of said shafts being provided with jaws for holding the head of a bobbin with unused yarn remaining thereon, the other of said shafts being an operating shaft for removing the yarn from the bobbin, said operating shaft being provided with eccentric means for causing the held bobbin to oscillate and being operative to rotate a cam for raising and lowering the bobbin holding shaft while the bobbin is oscillating.

6. A bobbin stripping machine having a plurality of upwardly extending substantially parallel shafts, one of said shafts provided with jaws for holding the head of a bobbin with unused yarn remaining thereon, the other of said shafts being an operating shaft, said operating shaft being provided at its upper end with means for causing the other shaft to oscillate and also being provided with means for operating a cam to cause said other shaft to reciprocate vertically, and said operating shaft operating means to engage said yarn.

7. A bobbin stripping machine having a pair of upwardly extending shafts, one of said shafts being provided with jaws for holding the head of a bobbin with unused yarn remaining thereon, an operating vertically extending shaft having

means to oscillate the shaft provided with jaws, said operating shaft also causing said first named shaft to reciprocate vertically, and means operable by said operating shaft engageable with the yarn remaining on the bobbin.

8. A bobbin stripping machine having a pair of substantially parallel upwardly extending shafts, one of said shafts being provided with jaws for engaging the head of a bobbin having unused yarn remaining thereon, the other of said shafts oscillating the shaft with the jaws and also having means for vertically reciprocating said oscillating shaft and for actuating means to engage said yarn.

9. A bobbin stripping machine having a vertically extending shaft rotatable about its axis and oscillating during its rotary movement, said shaft provided with jaws for holding the head of a bobbin, a clutch carried by said shaft and movable therewith for maintaining said jaws in engagement with the bobbin head, and means for moving said jaws out of engagement with said bobbin.

10. A bobbin stripping machine having a pair of upwardly extending shafts, one of said shafts being rotatable about its axis and oscillating during its rotary movement, said shaft provided with jaws for engaging the head of a bobbin having unused yarn remaining thereon, a clutch carried by said shaft and movable therewith for maintaining said jaws in engagement with the head of the bobbin, and means operable by the other one of said shafts for causing said clutch to disengage the jaws from the bobbin.

5 11. A bobbin stripping machine having an upright shaft rotatable about its axis and oscillating during its rotary movement, said shaft provided with jaws for holding the head of a bobbin, means for moving the shaft vertically, and clutch means carried by said shaft and movable therewith for causing said jaws to free said bobbin when said shaft is moved in one direction.

10 12. A bobbin stripping machine having a pair of upwardly extending rotatable shafts, one of said shafts having a plurality of fingers for holding the head of a bobbin with unused yarn thereon, means for maintaining said fingers in operative positions, the other shaft actuating a cam for vertically moving the shaft with said jaws and also operating a cam to actuate said means to cause said fingers to disengage said bobbin.
